A. D. GROVER

TAILPIECE FOR STRINGED MUSICAL INSTRUMENTS

Original Filed Dec. 14, 1921

Fig. 1.

Albert D. Grover

John C. Stennis

by Attn: Atty.

UNITED STATES PATENT OFFICE.

ALBERT D. GROVER, OF LONG ISLAND CITY, NEW YORK.

TAILPIECE FOR STRINGED MUSICAL INSTRUMENTS.

Application filed December 14, 1921, Serial No. 522,205. Renewed May 5, 1926.

My invention relates to improvements in tail pieces for stringed musical instruments.

One object of the invention is to provide a form of tail piece by means of which the 5 strings of the instrument will be adequately tensioned in proximity to the bridge, without danger of rupture to the strings as the result of the tensioning effect. Another object of the invention is to so construct the 10 string securing part of the tail piece as to adapt it for receiving strings with looped ends, or wire or gut strings with plain ends, all fraying or cutting of the strings being eliminated. A further object is the provision 15 of simple and effective means by which the tail piece may be securely attached to various kinds of stringed instruments without modifying the structure of the device. A still further object of the invention is to 20 generally simplify and improve the structure of such tail pieces, whereby their manufacture is rendered more economical than heretofore, and their use made more satisfactory.

25 The invention consists of certain novel structural features and coordinated elements of construction as will be hereinafter fully described, and defined by the appended claims.

30 Illustrative embodiments of the invention are shown in the accompanying drawing in which Fig. 1 is a plan view of a fragment of a stringed musical instrument, a banjo in this instance, with the improved tail 35 piece applied thereto; Fig. 2 is a substantially central vertical section through Fig. 1; Fig. 3 is a rear end elevation of Fig. 1; Fig. 4 is a plan of the completed blank, which when formed, constitutes the string 40 securing member of the tail piece; Fig. 5 is a longitudinal section on the line 5—5 of Fig. 4; Fig. 6 is a cross section on the line 6—6 of Fig. 3; and Fig. 7 is a vertical section of a slightly modified form of the 45 improved tail piece.

The general configuration of the tail piece is angular in cross section, and the device 50 comprises the top or head plate 10 and the rear or rim plate 11, these parts being preferably integral with and substantially at right angles to each other, the terms "head plate" and "rim plate" being arbitrarily selected to indicate rather generally that these plates are arranged adjacent the 55 head and rim, respectively, of the banjo. The plate 10 has depending reinforcing

flanges 12 which, when the tail piece is in position on the instrument, extend parallel to and are somewhat spaced from the head A of such instrument. Near its forward 60 end the plate 10 is provided with an elongated transverse slot 13, and in advance of this slot the front edge of the plate 10 is fashioned into a substantially ogee-shaped 65 curve 14, the downward dip of the portion 14 being nearest the bridge 15 over which the strings 16 pass. As best shown in Fig. 2 the strings 16 are tensioned by passing under the end 14 of the tail piece, and as this end is rounded in a direction generally 70 parallelizing the length of the string, the latter is held taut and close to the head A but without being subjected to any appreciable abrasion by contact with 14.

The rim plate 11 is provided with lateral 75 projections 17, and struck out from the web of the plate 11 is a lug 18 which is designed to rest against the rim of the banjo and prevent the plate 10 from being raised by the 80 pull of the strings 16 thereon.

At its lower end the plate 11 is provided with a flange 19 suitably orificed to receive the threaded bolt 20 which passes through the internally threaded lug 21 common to all similar stringed instruments. The flange 19 85 is held on the bolt 20 by collars 22 and the bolt itself is secured against accidental rotation by the guard nut 23 and the check nut 24. By means of the arrangement just described the tail piece is held rigidly in 90 position, so that displacement of the strings is prevented.

The string holder, which is well illustrated in Figs. 3 to 6, comprises the body portion 95 25 and the string receiving prongs which will be presently described. Struck up from the body 25 are lugs or ears 26 which are designed to be passed through slots 27 in the rim plate 11 (Fig. 6), and thereafter clinched or bent over whereby the string holder is 100 firmly secured to the plate 11. As shown in Fig. 6 when the ears 26 are bent over they contact with the top hoop of the banjo and thus assist in preventing the tail piece from 105 rocking transversely.

At one edge the string holder is provided with prongs or forked projections 28, and between each two adjacent prongs I form a slot 29 terminating in a rounded orifice 30. As is well known some string have looped 110 ends, others knotted ends, and still others plain ends, and the string holder described

and illustrated is adapted to receive any of these ends. If a string with a looped end is to be attached to the string holder such looped end is passed over one of the prongs 5 and come to rest in the orifices 30. In Figs. 1 and 3, the manner of securing a looped end is indicated at X, the two end strings being of the looped end type. If a string with a knotted end is to be secured 10 in position, the three intermediate strings in Figs. 1 and 3, designated Y, being of this variety, the portion of the string immediately next to the knot is passed into the bifurcation in one of the prongs 28 so that 15 the knot finds a purchase against the under-face of the material of the string holder adjacent the slot in the prong. When the string is tensioned its knotted end is firmly anchored as will be readily apparent without further explanation. If the end of the 20 string is entirely plain, that is without either a knot or a loop, the desirable manner of securing the same consists in passing the end of the string into one of the openings between the tines of the prong, then winding 25 a short length of the end upon itself, the orifices 30 being used for this purpose and in this manner the string when tensioned will be firmly secured in position.

30 For the purpose of preventing injury to the clothing of the player, I find it expedient to provide a cover for the tail piece, this cover being indicated at 31 and comprising a housing with lateral slotted guides 35 or extensions 32 which are designed to engage the lateral projections 17 of the rim plate 11. In cross section this cover has the general contour of the tail piece and may be readily moved into and out of engagement with the latter.

In Figs. 1 to 6 I have shown a type of tail piece in which the lug 18 is not movable in relation to the rim plate so that the spacing between the rim plate and the banjo 45 rim remains constant after the device is once applied to the instrument. Tail pieces of this construction are usually supplied to manufacturers of instruments, and the tail piece is in position when the instrument is sold. In Fig. 7 I have shown a form of device in which a screw 18^a, which corresponds in function to the lug 18, may be turned in one direction or the other to adjust the distance of the rim plate from the 50 banjo rim, as desired, and this type of tail piece is usually supplied to dealers who either sell the tail piece separately or who may wish to apply it to instruments of various makes. By providing the movable screw 18^a, the tail piece is made applicable to various types of instruments with the possibility of securing adjustment best suited to the instrument to which the device is applied. It will be understood that the purpose of the adjustment contemplated is to 55

keep the head plate 10 substantially parallel to the head of the instrument so as to properly tension the strings.

I desire, also, to call attention to the fact that the string holder may be readily applied to and removed from the tail piece, and consequently string holders having a greater or less number of string receiving instrumentalities than illustrated may be quickly and easily placed in position. 75

I have found by extended use of a tail piece such as herein described that it tends to very materially increase the tonal value and volume of the instrument to which it is applied, and that it is very economical in the matter of strings as the latter are not frayed or cut as is so frequently the case with tail pieces as at present constructed. 80

I claim:

1. In a tail piece for musical stringed instruments, the combination of a head plate, a rim plate integral therewith and having a slotted end portion disposed at an angle to the rim plate, and an adjustable member comprising a screw having a grooved head portion, the lateral walls of which engage above and below the walls of the slot in the end portion. 85

2. A tail piece for musical stringed instruments, comprising integral head and rim plates substantially at right angles to each other, said head plate having a transverse string receiving slot adjacent its front end, a substantially ogee curved front edge on said head plate, reinforcing flanges carried by the head plate, and means for securing the ends of the strings to said tail piece. 95

3. A tail piece for musical stringed instruments, comprising a head plate, a rim plate having slots therein, string securing means comprising a web portion having ears engaged in said slots, and string holding slotted projections integral with and extending at right angles to said web portion. 105

4. A tail piece for musical stringed instruments, comprising a head plate and a rim plate having lateral extensions, string securing means carried by said rim plate, and a removable tail piece having lateral guide grooves embracing said lateral extensions whereby relative movement of the cover is limited to the direction of the grooves. 110

5. A tail piece for musical stringed instruments, comprising a head plate, a rim plate, a lateral projection struck up from the rim plate for spacing the rim plate from the instrument rim, and string securing means carried by the tail piece. 120

6. A tail piece for musical stringed instruments, comprising a head plate, a rim plate having slots therein, string securing means, and projections on said string securing means passing through the slots in the rim plate and retaining the string securing means in position on the rim plate. 125

7. A tail piece for musical stringed instruments comprising a head plate and a rim plate integral one with the other, and means for holding the head plate in parallelism with the head of the instrument, said means comprising a tab struck up from the rim plate and extending at right angles from the central line of the rim plate into direct engagement with the rim of the instrument.
- 5 8. A tail piece for musical stringed instruments comprising a head plate and a rim

plate integral one with the other, and means for holding the head plate in parallelism with the head of the instrument, said means comprising a single tab struck up from the rim plate and extending at right angles from the central line of the rim plate into direct engagement with the rim of the instrument. 15

In testimony whereof I have affixed my signature.

ALBERT D. GROVER.
